UNITED STATES PATENT OFFICE.

CHARLES A. MOORE, OF EDINA, MINNESOTA.

REFRIGERATING APPLIANCE FOR PRECOOLING, COLD STORAGE, AND LIKE ROOMS.

Application filed September 28, 1925. Serial No. 59,085.

- My invention relates to improvements in overhead appliances for refrigerating pre-cooling, cold storage and like rooms, one object of the invention being to provide means for effecting refrigerated internal circulation of air within a room, also refrigerated ventilation therein, and a combination of both, all by gravity, or by gravity augmented by force from a blower.
- 10 Another and more specific object of the invention is to construct a refrigerating appliance in a simple and inexpensive manner, whereby the refrigerating element per se forms a duct system through and by which the circulation of air is effected.
- 15 With the foregoing and other objects in view, which will appear in the following description, the invention resides in the novel combination and arrangement of parts and 20 in the details of construction hereinafter described and claimed.
- 25 In the drawings, Fig. 1 is a view partly in plan and partly in section, the same illustrating an embodiment of my invention as applied to a room structure; Fig. 2 is a vertical, central, sectional view taken longitudinally of the appliance shown in Fig. 1; Fig. 3 is a detail sectional view taken on the line 3—3 of Fig. 2 and Fig. 4 is a similar view 30 taken on the line 4—4 of said Fig. 2.
- 35 Referring to the drawings, it will be noted that my improved appliance occupies a position in the upper portion of a room structure, the walls and ceiling of which are designated, respectively by the numerals 10 and 11. Said appliance includes a refrigerating element made up of plate-like, end forming headers 12, 13, and skeleton sides *a*, top *b*, bottom *c* and intermediate horizontal partitions *d*, 40 each comprising spaced, refrigerant conducting pipes 14 supported at their opposite ends by and communicating with said headers 12, 13. Hangers 15 depending from the ceiling 11 and fastened to the headers 12, 13 carry 45 the appliance with the top thereof near, but spaced from the ceiling 11. A refrigerant feed pipe 16, fitted with a valve 17, opens into the header 12 near the bottom thereof and a return pipe 18, fitted with a valve 19, 50 is connected with the header 13 near the top thereof. Upon circulating a refrigerant through the header 12, pipes 14 and header 13, all of said elements become frost or ice coated, the pipes 14 to such an extent as to 55 close the spaces between them, except at certain places hereinafter referred to. The frost or ice, thus resolving the skeleton sides *a*, top *b*, bottom *c* and partition *d* into solid wall-like parts, provides two ducts *E*, *F* (Fig. 3), the former superimposing the latter. Medially of the top *b* of the refrigerating element, constituted by said duct structure, is a relatively wide space between the pipes 14. This space is too wide to be bridged by frost accumulating on said pipes and it provides 60 an elongated port *e* in the upper duct *E*. A similar port *f* in the bottom *c* of the refrigerating element is provided in a similar wide space between pipes 14. At the end of said element, next to the feed header 12, the intermediate pipes 14 of the partition *d* fall short of said header, the ends of said shortened pipes being connected through fittings 20 with the adjacent pipes 14 extending on to the header 12. Thus constructed, a passageway *d'* is provided in the partition *d* between the ducts *E*, *F*. A gate 21, hinged on the inner face of the header 12 and actuated through a turn rod 22, equipped with a hand wheel 23, obstructs or clears said passageway 70 *d'*, as may be desired. A conduit 24 communicating at its upper end with the outer air hangs downward through the ceiling 11, the lower end of said conduit opening above the port *e* in the upper duct *E*. A second and 75 intermediate conduit 25, opening at its outer end into the outer air, extends through the wall 10 and header 12 into the lower duct *F*. Said conduits 24, 25 are provided, respectively, with dampers 26, 27. A blower *h*, resting 80 on a shelf 28 secured to the header 12, is supported within the lower duct *F*, the fan 29 of said blower turning in a vertical plane removed slightly inwardly from the passageway *d'* in the partition *d*, said fan being 85 adapted to set up a current of air through said duct *F* toward the end thereof opposite the blower *h*.
- 90 In use, the valve 17 of the feed pipe 16 is opened and the valve 19 of the return pipe 18 similarly adjusted. Circulating through the header 12, pipes 14 and header 13, a refrigerant therein causes the building up of frost and ice on said parts, the walls of the ducts *E*, *F* ultimately being sealed closed, 95 the ports *e*, *f*, however, and the passageway *d'* remaining open. With the blower *h* idle and the gate 21 clear of the passageway *d'* in the partition *d* and the dampers 26, 27 closed, internal refrigerated circulation is set 100 up within the room by gravity. The air refrigerated in the lower duct *F* passes down-

ward through the port *f* toward the floor, thence to the warmer walls and upward to the ceiling, thence downward through the port *e* into the upper duct *E*, and thence 5 through the passageway *d'* in the partition *d* to said lower duct *F*. The opening of the dampers 26, 27 in various degrees, results in mixed refrigerated circulation and ventilation. The circulation of air under the dif- 10 ferent conditions above noted is brought about solely through gravitation, when the blower *h* is idle, but with said blower in operation such circulation of air is augmented by the action of the fan 29. With the gate 21 15 closed and the fan 29 in motion, air may be drawn into the duct *F* through the conduit 25 and expelled from the room through the conduit 24. Under this condition forced refrigerated ventilation is effected.

20 Among the important features resident in my present appliance, is the advantageous organization of parts whereby the refrigerating element is in itself resolved into a particularly effective duct system for causing 25 the convective and diffused circulation of air refrigerated thereby.

Changes in the specific form of my invention, as herein disclosed, may be made within the scope of what is claimed without departing 30 from the spirit of my invention.

Having described my invention, what I claim as new and desire to protect by Letters Patent is:

1. The combination with a room of a horizontal elongated skeleton-like structure including ends and sides, also a top with an air ingress port therein and a bottom with an air egress port therein, also a horizontal partition between top and bottom terminating, 35 at one extremity, short of one of said ends, the same forming walls of superimposed ducts communicating one with the other, said walls comprising refrigerant pipes relatively arranged and adapted, upon the accumulation 40 of frost thereon, to be rendered solid, except along said ports.

2. The combination with a room of a refrigerating appliance therefor including a duct structure comprising skeleton walls 50 made up of a plurality of refrigerant pipes relatively arranged to allow for the frosting together of said pipes upon the accumulation of ice thereon, a feed header common to said pipes, a return header also common to 55 said pipes, and a fan within the duct structure for blowing air therethrough, said fan being arranged at the end of said structure adjacent to said feed header.

3. The combination with a room of an overhead refrigerating appliance therefor including a horizontal elongated duct formed with two elongated ports therein, one above the other, said duct having ends and skeleton walls, each end comprising a plate-like 65 header, the walls comprising pipes carried

by and communicating at their opposite ends with said headers, said pipes being relatively arranged to become frosted together and to form solid walls defining said parts, a refrigerant feed pipe leading to one of said 70 headers and a refrigerant return pipe leading from the other header.

4. The combination with a room of an overhead appliance therefor including a pair of horizontal elongated ducts, one communicating 75 at one end thereof with one end of the other duct, said ducts including skeleton-like top, side and bottom walls composed of parallel refrigerant pipes, mainly arranged in near proximity, one with respect to another, and adapted to be rendered solid by the frosting together of said pipes, two of the adjacent pipes in each of said ducts being sufficiently separated to provide a port, the port in one duct being nearer to the ceiling than the port 80 in the other duct.

5. The combination with a room of a refrigerating appliance therefor including a system of horizontal elongated ducts inter- 90 communicating at corresponding ends thereof and co-operating to set up a circulation of air in the room, each duct including walls composed of refrigerant pipes, all except one wall of each duct being adapted to be rendered solid by the frosting together of said 95 pipes and said excepted wall of each duct being likewise rendered solid save at a portion in one duct to provide for the ingress of air thereto and at a portion in the other duct to provide for the egress of air therefrom.

6. The combination with a room of an overhead refrigerating appliance therefor including a horizontal elongated duct open at the upper portion thereof to receive air from the upper portion of the room and open at the 100 lower portion thereof to deliver refrigerated air therefrom, said duct comprising an upright inlet header, an upright outlet header, and a plurality of horizontal refrigerant pipes carried by and communicating at 105 their opposite ends with said headers, said headers forming the ends of the duct, said pipes forming the walls of the duct and being relatively arranged, whereby the same may be frosted together by the accumulation 110 of ice thereon.

7. The combination with a room of a dual duct structure including two vertically spaced walls and a horizontal partition disposed medially of said walls, said partition 120 and walls containing a circulating refrigerant, the space between the walls above the partition forming an upper duct open along the top thereof for the ingress of air there- 125 to, the space between the walls beneath the partition forming a lower duct open along the bottom thereof for the egress of air therefrom, the structure providing an air passage- 130 way from one end of the upper duct to the corresponding end of the lower duct.

8. The combination with a room of an overhead duel duct structure including two vertically spaced walls and a horizontal partition disposed between said walls, said partition and walls consisting of refrigerant pipes relatively arranged, whereby the same may be frosted together by the accumulation of ice thereon, the spaces between the walls above and beneath the partition respectively providing a suction duct and an exhaust duct, the former being open along the top thereof near the ceiling of the room and the latter open along the bottom, and a fan arranged to draw air from the suction duct and blow it into the exhaust duct.
9. The combination with a room of an overhead elongated skeleton-like structure including sides and a bottom with an air egress port therein, said sides and bottom comprising refrigerant pipes relatively arranged and adapted, upon the accumulation of frost thereon, to be rendered solid, except along said port, whereby a duct is formed open along the bottom thereof, and a conduit leading into the room from the outside to said duct.
10. The combination with a room of an overhead elongated skeleton-like structure including sides and a bottom with an air egress port therein, said sides and bottom comprising refrigerant pipes relatively arranged and adapted, upon the accumulation of frost thereon, to be rendered solid, except along said port, whereby a duct is formed open along the bottom thereof, and a fan arranged to draw air from the suction duct and blow it into the exhaust duct.
11. The combination with a room of an overhead elongated skeleton-like structure including sides comprising refrigerant pipes relatively arranged and adapted upon the accumulation of frost thereon, to be rendered solid and thereby form an elongated duct opening at the top near the ceiling of the room and opening at the bottom thereof at a lower elevation, and a conduit leading from without the room to said duct.
12. The combination with a room of an overhead elongated skeleton-like structure including sides comprising refrigerant pipes relatively arranged and adapted upon the accumulation of frost thereon, to be rendered solid and thereby form an elongated duct opening at the top near the ceiling of the room and opening at the bottom thereof at a lower elevation, a conduit leading from without the room to said duct, and a fan associated with said conduit for drawing air into the room from the outside and impelling it into said duct.

In testimony whereof, I have signed my name to this specification.

CHARLES A. MOORE.

CERTIFICATE OF CORRECTION.

Patent No. 1,722,817.

Granted July 30, 1929, to

CHARLES A. MOORE.

It is hereby certified that error appears in the printed specification of the above numbered patent requiring correction as follows: Page 2, line 69, claim 3, for "solid walls defining said parts" read "solid walls defining said ports"; page 3, line 2, claim 8, for the word "duel" read "dual"; and that the said Letters Patent should be read with these corrections therein that the same may conform to the record of the case in the Patent Office.

Signed and sealed this 10th day of September, A. D. 1929.

M. J. Moore,
Acting Commissioner of Patents.

8. The combination with a room of an overhead duel duct structure including two vertically spaced walls and a horizontal partition disposed between said walls, said partition and walls consisting of refrigerant pipes relatively arranged, whereby the same may be frosted together by the accumulation of ice thereon, the spaces between the walls above and beneath the partition respectively providing a suction duct and an exhaust duct, the former being open along the top thereof near the ceiling of the room and the latter open along the bottom, and a fan arranged to draw air from the suction duct and blow it into the exhaust duct.
9. The combination with a room of an overhead elongated skeleton-like structure including sides and a bottom with an air egress port therein, said sides and bottom comprising refrigerant pipes relatively arranged and adapted, upon the accumulation of frost thereon, to be rendered solid, except along said port, whereby a duct is formed open along the bottom thereof, and a conduit leading into the room from the outside to said duct.
10. The combination with a room of an overhead elongated skeleton-like structure including sides and a bottom with an air egress port therein, said sides and bottom comprising refrigerant pipes relatively arranged and adapted, upon the accumulation of frost thereon, to be rendered solid, except along said port, whereby a duct is formed open along the bottom thereof, and a fan arranged to draw air from the suction duct and blow it into the exhaust duct.
11. The combination with a room of an overhead elongated skeleton-like structure including sides comprising refrigerant pipes relatively arranged and adapted upon the accumulation of frost thereon, to be rendered solid and thereby form an elongated duct opening at the top near the ceiling of the room and opening at the bottom thereof at a lower elevation, and a conduit leading from without the room to said duct.
12. The combination with a room of an overhead elongated skeleton-like structure including sides comprising refrigerant pipes relatively arranged and adapted upon the accumulation of frost thereon, to be rendered solid and thereby form an elongated duct opening at the top near the ceiling of the room and opening at the bottom thereof at a lower elevation, a conduit leading from without the room to said duct, and a fan associated with said conduit for drawing air into the room from the outside and impelling it into said duct.

In testimony whereof, I have signed my name to this specification.
